UNITED STATES PATENT OFFICE.

ALBERT R. THOKE, OF PITTSBURGH, AND HUBERT G. SMITH, OF WILKINSBURG, PENNSYLVANIA.

THREADING TOOL.

Application filed March 7, 1922. Serial No. 541,652.

To all whom it may concern:

Be it known that we, ALBERT R. THOKE and HUBERT G. SMITH, citizens of the United States, and residents of Pittsburgh and Wilkinsburg, respectively, in the county of Allegheny and State of Pennsylvania, have invented a new and useful Improvement in Threading Tools; and we do hereby declare the following to be a full, clear, 10 and exact description thereof.

Our invention relates to a threading-tool, and particularly to die-heads of the type adapted for use in turrets and similar supports of screw-threading machines.

15 The object of our invention is to provide a tool of this character which is simple in construction and made up of a minimum number of parts, and which will automatically retract the dies at the limit of their 20 threading movement, as well as to improve such machines in other features.

In the accompanying drawings Fig. 1 is a front view of our improved tool; Fig. 2 is a section taken on the line 2-2, Fig. 1; 25 Fig. 2^a is an end view of the cam wrench; Fig. 3 is a cross-section taken on the line 3-3, Fig. 2; Fig. 4 is a section on the line 4-4, of Fig. 3; Fig. 5 is a half section corresponding to the upper half section of Fig. 30 2, showing the threading-dies in their advanced position; Fig. 6 is a section corresponding to the upper-half of Fig. 4, showing the threading dies in advanced position; Fig. 7 is a section taken diagonally opposite to the lower-half of Fig. 2; Fig. 8 is a section corresponding to the upper-half of Fig. 2 showing the threading dies withdrawn; Fig. 8^a is a portion of the front of 35 the tool with the threading-die in the position shown in Fig. 8; Fig. 9 is a view corresponding to the upper-half of Fig. 2, showing the threading-dies extended and expanded, the cam-ring having moved around to bring the groove of the cam over 40 the threading die; Fig. 9^a is a front view of a portion of the tool showing the position of the parts of Fig. 9; Fig. 10 is a view corresponding to the upper part of Fig. 2, the 45 threading-dies being drawn back on the cam-ring which is ready to be caught by hand or otherwise to put the cam-ring back to the position of Fig. 1; and Fig. 11 is a 50 sectional detail showing the worm and

worm-wheel for operating the adjustment of the cam-ring for size adjustment. 55

The numeral 2 designates a suitable shell or casing which is screwed fast to the spindle 3. Within the shell 2 is the head or block 4 which has a sliding fit within the bore of the shell 2. The head 4 is connected 60 by means of the screws 6 to the chaser-block 5. The threading dies or chasers 7 are adapted to move in and out in guides in said chaser-block, and are secured to the block 8 by screws 9. The block 8 has the angular 65 cam-slots 8^a which are engaged by the wedge-portions 10 of the die retracting member 11 which surrounds the head 4 and has sliding engagement therewith. The die retracting member 11 is normally pressed 70 forward by the springs 12, said springs fitting in a recess 13 in said member and interposed between the forward end of said seat and the enlargement 14 on the pin 15, the rear end of said enlargement engaging the 75 shoulder 16 on the head 4. There is only one pin 15, and in the other instances the rear ends of the springs 12 enter seats 17 in the head 4.

The head 4 is provided with the recesses 80 18 to receive the springs 19, said springs being interposed between the rear ends of said recesses and the heads 20 of the bolts 21 connected to the shell or casing 2. The springs 19 act to hold back the head 4 normally in the position shown in Fig. 4.

Mounted on the shell 2 is the outer-shell or casing 22, and secured to said outer-casing, by means of the screws 24, is the cam-ring 23 having the cam-faces 25 with the 90 grooves 26, 26^a formed at the ends thereof to receive the threading dies, as will more fully hereinafter appear.

Formed in the chasers or dies 7 are the notches 27 which normally register with the 95 grooves 26, 26^a formed in the cam-ring 23. The formation of the notches 27 in the dies 7 forms corresponding lugs 28 and 29, so that when said dies are advanced to the position shown in Fig. 8, said lugs 28 will overlap the outer face of the cam-ring 23, and the lugs 29 will enter the foremost grooves 26. As the blocks 8 are connected to the 100 threading dies 7 the lugs 30 on said blocks will then enter the rearmost grooves 26^a of the cam-ring.

- Formed on the inner-shell 2 are the lugs 31 and on the outer shell 22 the lugs 32, the lugs 31 on the casing 2 entering the annular groove 34 formed in the outer-casing 22.
- 5 Springs 35 are interposed between the lugs 31 and 32, said springs being adapted to bring the outer-shell 22 and the cam-ring 23 back to normal position, as will more fully hereinafter appear.
- 10 At the rear of the inner-casing 2, and interposed between said casing and the inwardly extending flange 36 of the outer-casing, is the worm-wheel 37. A worm 38 journaled in the outer-casing 22 engages the worm-wheel 37, and as said worm-wheel has the opening 39 which receives the outer end of the pin 15 it will be apparent that when the worm 38 is rotated the outer-casing will be turned to compress the springs 35.
- 15 To provide for advancing the head 4 manually where desired, a cam 40 on the shaft 42 is adapted to engage the pin 43 extending through the outer casing 2 and adapted to bear against the inner end of the head 4.
- 20 The operation of our improved tool is as follows:
- The threading dies 7 are first adjusted by turning the cam-ring 23 which is done by turning the worm 38, the cam-faces of said cam-ring being in engagement with the threading-dies, said dies will be moved inwardly in proportion to the amount of rotary movement imparted to the cam-ring 23. When the cam-ring has been adjusted so as to bring the dies into proper position for threading the work, the work is rotated and the spindle 3 carrying the threading tool, is held from rotation or vice versa but is advanced longitudinally and the thread is formed on the work. When the length of thread desired has been formed the spindle 3 is reversed by suitable reversing mechanism or stopped, and as the threading-tool starts to withdraw, or dies continue to advance due to the thread, the threads of the threading-dies being still in engagement with the work, there will be an outward pull on said threading-dies, and this pull will bring the parts to the position indicated in Figs. 5 and 6, the pin 15 being withdrawn from the opening 39. At this point the lugs 28, 29 and 30 are ready, the former to overlap the outer end of the cam-ring and the latter two to enter the grooves 26 and 26^a.
- 25 At this instant the springs 12 come into play and advance the retracting member 11 so that the wedge-portions 10 engaging the blocks 8 force said blocks outwardly, driving the lugs 30 into the grooves 26 and the lugs 29 into the groove 26, bringing the parts into the position shown in Fig. 8. By the forward movement of the die-blocks 5 the head 4 will be advanced, putting the springs 19 under compression, and at the same time the pin 15 is withdrawn from engagement with the worm-wheel 37, as shown in Fig. 5. The springs 35 which have been compressed by the previous adjusting of the cam-ring 23 to bring the threading-dies into proper position, now act to return said cam-ring to the position shown in Figs. 9, 9^a, bringing the threading-dies into register with the notches 26^b at the ends of the cam-faces 25 shown in Fig. 9^a.
- The outer shell is then turned by the handle 45 in a reverse direction to that which was imparted to it by the springs 35. This rotary movement is continued until hole 36 is brought into alignment with pin 15, at which instant the pin 15, actuated by spring 12 in piece 10, plunges into the opening 39 and thus relocates cam-ring in original position and consequently restores setting of die ready to repeat the operation, as in Figs. 1, 2, 3 and 4.
- 30 What we claim is:
1. In a threading-tool, the combination of a suitable casing, a cam-ring having rotary relation with said casing, a spring actuated slideable head in said casing, die-blocks connected to said head, dies movable in and out in said die-blocks, notches formed in said dies forming lugs adapted to engage grooves formed in said cam-ring and the front face of said ring when said dies 95 are advanced beyond the face of said cam-ring, means for retracting said dies, and means for automatically turning said cam-ring when said dies are advanced.
2. In a threading-tool, the combination 100 of a suitable casing, a spring actuated cam-ring having rotary relation with said casing, a spring actuated slideable head in said casing, die-blocks connected to said head, dies movable in and out in said die-blocks, notches formed in said dies forming lugs 105 adapted to engage grooves formed in said cam-ring and the front face of said ring when said dies are advanced beyond the face of said cam-ring, and means for re- 110 tracting said dies.
3. In a threading-tool, the combination 115 of a suitable casing, an outer casing surrounding said first casing, a cam-ring connected to said outer casing, stops on said inner-casing, stops on said outer-casing, springs interposed between the stops on said outer-casing and the stops on said inner-casing, means for rotating said outer-casing, a spring actuated slideable head in 120 said casing, die-blocks connected to said head, dies movable in and out in said die-blocks, means for bringing said dies into inter-engaging relation with said cam-ring when said dies are advanced, and means 125 for retracting said dies.
4. In a threading-tool, the combination 130 of a suitable casing, an outer casing surrounding said first named casing, a cam-ring connected to said outer casing, stops

on said inner and outer-casings, springs engaging the stops on said inner and outer-casings, a worm-wheel on said inner casing, a worm in said outer-casing engaging said 5 worm-wheel, whereby said outer casing is rotated to compress said springs, a spring actuated slidable head in said inner-casing, a bolt on said head engaging an opening in said worm-wheel, die-blocks connected 10 to said head, dies movable in and out in said die blocks, means for bringing said dies into interengaging relation with said cam-ring when said dies are advanced beyond said cam-ring, whereby said head is 15 likewise advanced and said bolt is withdrawn from said worm-wheel to permit said outer-casing carrying said cam-ring to rotate.

5. In a threading-tool, the combination 20 of a suitable casing, a spring actuated cam-ring having rotary relation with said casing, a spring actuated slidable head in said casing, die-blocks connected to said head, dies movable in and out of said die-blocks, 25 means for bringing said dies into interengaging relation with said cam-ring when said dies are advanced, and spring actuated

wedge-members adapted to engage said dies to retract the same when said dies are advanced.

6. In a threading-tool, the combination 30 of a suitable casing, a spring actuated cam-ring having rotary relation with said casing, a spring actuated slidable head in said casing, die-blocks connected to said head, 35 dies movable in and out in said die-blocks, blocks connected to said dies having beveled faces and openings formed therein, spring actuated wedge-members adapted to engage 40 said beveled faces and enter said openings, means for bringing said dies and said cam-ring into interengaging relation when said dies are advanced, whereby when said dies are advanced said spring actuated wedge-members advance, engaging said beveled 45 faces of said blocks to retract said dies.

In testimony whereof, we, the said ALBERT R. THOKE and HUBERT G. SMITH, have hereunto set our hands.

ALBERT R. THOKE.
HUBERT G. SMITH.
